United States Patent Office

Des. 185,115
Patented May 12, 1959

185,115

COMBINED FUNNEL AND FRAME THEREFOR

Jack Beerman, Newark, N.J.

Application April 28, 1958, Serial No. 50,650

Term of patent 14 years

(Cl. D44—10)

Fig. 1

Fig. 2

Fig. 4

Fig. 3

Figure 1 is a perspective view of a combined funnel and frame therefor, showing my new design, a fragmentary portion of a jar being shown in broken lines for purposes of illustration.

Figure 2 is a top view thereof.

Figure 3 is a bottom view.

Figure 4 is a side view.

I claim:

The ornamental design for a combined funnel and frame therefor, as shown and described.
